SANDWICH-MAKING DEVICE

Louis Don, Milford, Conn.

Application April 26, 1952, Serial No. 284,593

12 Claims. (Cl. 107—1)

This invention relates to an improvement in sandwich-making devices. The invention relates more particularly to a device for making sandwiches, the latter comprising food articles such as rolls and frankfurters or the like.

One object of the invention is to provide an improved sandwich-making device.

Another object is to provide a unitary and portable sandwich-making device meeting all sanitation requirements.

Still another object is to provide a device of the character described having few and simple parts, and which is easily operated and trouble free.

Still other objects of the invention will appear hereinafter.

In the accompanying drawings:

Fig. 1 is a front elevation of a sandwich-making device embodying the principles of the present invention;

Fig. 2 is a side elevation of the device shown in Fig. 1 looking toward the right;

Fig. 3 is a side elevation of the device shown in Fig. 1, certain parts being broken away and looking toward the left;

Fig. 4 is a sectional view on line 4—4 of Fig. 2;

Fig. 5 is a sectional view on line 5—5 of Fig. 1;

Fig. 6 is a broken sectional view on line 6—6 of Fig. 1;

Fig. 7 is a sectional view on line 7—7 of Fig. 2, with certain parts being broken away;

Fig. 8 is a sectional view on line 8—8 of Fig. 7;

Fig. 9 is a perspective view of the bottom part of the sandwich-assembling means of the invention; and

Fig. 10 is a perspective view of the top part of the sandwich-assembling means of the invention.

In the drawings, a casing, preferably constructed of sheet metal, is indicated generally by the numeral 10. The casing 10 includes two hollow drums 11 and 12 axially aligned and laterally spaced apart; the drums 11 and 12 being closed at their inner and opposing ends and providing reservoirs for rolls and frankfurters, respectively. Detachable caps 13 and 14, preferably constructed of sheet metal, close the outer ends of the drums 11 and 12, respectively. The caps 13 and 14 are the slip-on type and each is provided with a plurality of spring clamps 14a arranged around the periphery thereof and suitably fixed thereto and engageable with the respective drums 11 and 12, as shown in Fig. 1 of the drawings. The drums 11 and 12 are interconnected by an elbow 15, the sides of the elbow 15 being secured to the respective ends of the drums 11 and 12 in any suitable manner, as by welding. The elbow 15 is provided with an upwardly extending portion 16, and is also provided with a horizontally disposed forwardly extending portion 17, the latter being dished. Supported in the dished portion 17 of the elbow is a channeled member 18, the channel facing the drum 12, and the channeled member 18 supporting in turn a flat horizontally disposed member or bed 19 extending between the drums 11 and 12. The bed 19 supports sandwich-assembling means indicated generally at 20. The sandwich-assembling means 20 will be described hereinafter.

A shaft 21 extends through the drums 11 and 12 and the caps 13 and 14, the shaft being suitably journaled in the inner and opposing ends of the drums 11 and 12; and generally cylindrical sheet-metal food-supporting frames 22 and 23 are located in the drums 11 and 12, respectively, and fixed to the shaft 21 to rotate therewith. The frame 22 supports a plurality of rolls or the like, and the

frame 23 supports a plurality of frankfurters or the like, and the frames 22 and 23 may be rotated together on the shaft 21 by manipulation of a knob 24 detachably secured to one end of the shaft 21. The food-supporting frames 22 and 23 will be more fully described hereinafter.

The food-supporting frame 22 located in the drum 11 (see Fig. 6) comprises an inner sleeve 25 disposed over the shaft 21, and suitably secured thereto. Spaced apart and located radially outwardly and concentrically of the sleeve 25 are sleeves or cylinders 26, 27, and 28 separated and rigidly supported from each other and from the sleeve 25 by struts 29 disposed circumferentially thereof, and suitably secured to the adjacent sleeves as by welding. The sleeves or cylinders 26, 27 and 28 are open at their ends, the arrangement being such that rolls may be supported in the cylinders 26, 27 and 28 between the struts 29. The rolls are cut part way through longitudinally thereof, as is customary (see Fig. 6), and a member 30 L-shaped in cross section may be welded to each strut 29, the L-shaped member 30 having a leg extending into the cut and engageable with the roll to inhibit displacement of the latter with respect to the frame 22, as shown in Fig. 6.

The food-supporting frame 23 located in the drum 12 (see Fig. 5) comprises an inner sleeve 31 disposed over the shaft 21, and suitably secured thereto. Spaced apart and located radially outwardly and concentrically of sleeve 31 are sleeves or cylinders 32 and 33. A plurality of inverted channeled members 34 are arranged circumferentially of each of the sleeves 31, 32 and 33, the channeled members 34 being disposed on the outer surfaces of the sleeves and secured thereto as by welding. Plate members 35 extending from the channeled members 34 on the sleeves 31 and 32 to the next outer sleeve and welded thereto rigidly support the sleeves 32 and 33 from each other and from the sleeve 31. The sleeves or cylinders 32 and 33 are open at their ends, the arrangement being such that frankfurters may be supported one in each of the channeled members 34.

As indicated in Fig. 4 of the drawings, the sleeves 26, 27 and 28 of the frame 22 may be perforated. The channeled members 34 of the frame 23 may also be perforated.

To remove the cap 13, a retaining collar 36 detachably secured on the left end of the shaft 21 as by a clamping screw 36a is first removed. The cap 13 may then be pulled off the drum 11. To remove the cap 14, the knob 24 detachably connected to the other end of the shaft 21 as by a clamping screw 24a is first removed. The cap 14 may then be pulled off the drum 12. The manner in which the aforementioned food articles are inserted in the frames 22 and 23 in the drums 11 and 12, respectively, will be evident from the foregoing.

As shown in Figs. 2 and 3 of the drawings, each of the caps 13 and 14 is provided with three apertures 37 substantially in line, and a collar 38 surrounds each of the apertures 37 and is secured to the respective cap as by welding. Three slideable plungers 39 are located in the respective collars 38 secured to the cap 13, and three slideable plungers 40 are located in the respective collars 38 secured to the cap 14. As shown in Fig. 7, a rod 41 may be provided for connection to the outer end of any one of the three plungers 39, and a rod 42 may be provided for connection to the outer end of any one of the plungers 40. Each of the rods 41 and 42 may be detachably fastened to any one of the respective plungers 40 and 41 by a cross pin 42a providing a hinged connection (see Fig. 1 of the drawings). As shown in Fig. 6, a notched plate member 43 is suitably connected to the inner end of each of the plungers 39 to provide a roll pusher; and, as shown in Fig. 5, a disk member 44 is suitably connected to the inner end of each of the plungers 40 to provide a frankfurter pusher.

As shown in Figure 7, a slot 45 is formed in the inner end of the drum 11 registering with the sleeves or cylinders 26, 27 and 28 and the apertures 37 formed in the cap 13. Thus the rod 41 may be connected to any one of the plungers 39 and manipulated to push a roll, which may be in alignment therewith, out of the frame 22 and out of the drum 11 through the slot 45, the rod

41 being slidable in the drum 11. As shown in Fig. 8, there are three apertures 46 in the inner end of the drum 12, and the apertures 46 are registerable with the frankfurter spaces of the frame 23 and register with the apertures 37 formed in the cap 14. A flap 46a may be provided over each of the apertures 46 to close the same, the flap 46a being suitably hinged to the inner end of the drum 12 so that the flap may swing upwardly. From the foregoing, it will be understood that the rod 42 may be connected to any one of the plungers 40 and manipulated to push a frankfurter, which may be in alignment therewith, out of the frame 23 and out of the drum 12 through one of the apertures 46, the rod 42 being slidable in the drum 12.

It will be understood that the slot 45 in the drum 11 registers with the apertures 46 in the drum 12.

The sandwich-assembling means 20 supported on the bed 19 is located between the slot 45 and the apertures 46. As shown in Figs. 9 and 10, the sandwich-assembling means comprises a lower part indicated generally by the numeral 47, and an upper part indicated generally by the numeral 48, the parts 47 and 48 being preferably of cast metal. The part 47 is elongated and generally trough-shaped, the sides 49 thereof being cut away at 50 intermediate their ends. The trough-shaped part 47 is open at one end and has an abutment 51 at the other end, the abutment 51 being cut away on an arc at 52. Cooperating with the trough-shaped part 47 is the upper part 48, the latter being a generally rectangular plate and provided with a lug 53 at each corner thereof engageable with corner surfaces 53a on the trough-shaped part 47 for support thereby. The plate part 48 has a top 54 extending longitudinally thereof intermediate the sides. Surrounding the top 45 on three sides thereof is a depending flange 55 generally of U shape and having its legs extending to one end of the plate part 48. The outer surfaces of the legs of the flange 55 meet in a ridge 55a, as shown in Fig. 10. As indicated in Figs. 7 and 8, the trough-shaped part 47 carries pins 56 at the underside thereof, one at each end, and the bed 19 is provided with recesses 56a to receive the pins 56, the recesses 56a being so positioned that the trough-shaped part 47 may be aligned with any one of the apertures 46, as indicated in Fig. 8. The plate part 48 may be secured to the underside of a closure member 57 constructed of sheet metal and hinged to a bracket 58 to swing upwardly, the latter being suitably fastened to the bed 19. Two thumb screws 59 may be provided for securing the plate part 48 to the closure member 57, the plate part 48 having two threaded holes, one at each end of the plate member, to receive the thumb screws 59. The thumb screws 59 may be passed through the closure member 57 so that the plate part 48 may be aligned with any of the apertures 46, the plate part 48 always being positioned directly over the trough-shaped part 47.

From the foregoing, it will be understood that when the rods 41 and 42 are aligned with the plungers to which they are hinged, as shown in Fig. 1 in dotted lines, the rods 41 and 42 may be pushed into the drums 11 and 12, respectively, feeding a roll and a frankfurter to the sandwich-assembling means 20. To assure alignment of the rods 41 and 42 with a frankfurter and a roll, respectively, a leaf spring 60 is secured at one end thereof to the left end of the trough-shaped part 47, the spring being located in a transverse slot 61 formed in the trough-shaped part 47 and the spring 60 having a part 62 at the other end of the spring 60 engageable with any of the struts 29 of the frame 22, and movable into the slot 61 in the trough-shaped part 47 against the pressure of the spring 60, the arrangement being such that the part 62 is urged out of the slot 61 to resist rotation of the frames 22 and 23 by engagement with any of the struts 29, the rods 41 and 42 being aligned with a frankfurter and a roll, respectively, when the part 62 is so engaged. The part 62 is so shaped that the struts 29 ride over the part 62 against the pressure of the spring 60 when the frames 22 and 23 are rotated in either direction. It will be understood that the frames 22 and 23 are fixed to the shaft 21 and are in alignment with each other, the shaft 21 being rotatable manually by means of the knob 24.

In the operation of the device, the rod 41 is first used as described above to feed a roll to the sandwich-assembling means 20, the roll moving into the trough-shaped part 47 and being opened longitudinally by the ridge 55a of the flange 55. Movement of the roll may be arrested

by engagement of the latter with the abutment 51 on the trough-shaped part, the sandwich-assembling means 20 comprising the trough-shaped part 47 being positioned so as to be aligned with the plunger to which the rod 41 is connected. The rod 42 connected to the plunger aligned with the sandwich-assembling means 20 is then used as described above to feed a frankfurter to the sandwich-assembling means 20, the plate part 48 being disposed with the U-shaped depending flange 55 facing toward the frame 23, the latter guiding the frankfurter as it moves into the opened roll. Movement of the frankfurter may be arrested by engagement of the latter with the intermediate portion of the U-shaped flange 55. When the frankfurter is in this position the sandwich is assembled. The closure member 57 may then be opened to the position shown in Fig. 8 in dotted lines, and the sandwich lifted out of the trough-shaped member 47. When the closure member is again in lowered position, the operation may be repeated after first rotating the frames 22 and 23 by the knob 24 until the part 62 engages the next following strut 29 of the frame 22. The preferred practice is to connect the rods 41 and 42 to the outermost plungers 39 and 40, respectively, the sandwich-assembling means 20 being positioned as shown in Fig. 8, and exhausting the radially outermost rolls and frankfurters, then progressively moving the rods 41 and 42 inwardly to the next plungers 39 and 40, respectively, and progressively moving the sandwich-assembling means 20 to the next inner position. When the rolls and frankfurters are completely exhausted, the caps 13 and 14 may be removed from the drums 11 and 12, respectively, as described above, and the frames 22 and 23 refilled, and the caps 13 and 14 replaced.

A heating element may be provided in association with the sandwich-making device to warm or cook food while the latter is in the device. In the preferred embodiment of the invention illustrated in the drawings, a sheet-metal water tank 63 is provided under the drum 12 and secured thereto as by welding (see Fig. 1 of the drawings). Under the tank 63 is a burner unit 64 comprising a suitable fuel reservoir, the unit 64 being supported from the tank 63 by a bracket 65, the latter preferably being welded to the tank. The drum 12 is provided with a suitable inner insulating lining 66 having an opening 67 formed therein. The opening 67 registers with an opening 67a in the drum 12. A baffle plate 68 is located over the openings 67 and 67a and secured to the drum 12 as by welding. The baffle plate 68 is perforated to receive one end of a conduit 69, the other end of the conduit 69 opening into the tank 63. The tank 63 is provided with a capped intake conduit 70, and may also be provided with a drain cock 71. A pair of drain conduits 72 lead through the lining 66 into the tank 63. The arrangement is such that heat generated by the burner 64 causes steam to be generated in the tank 63, the steam passing into the drum 12 through the conduit 69 and passing through the perforations in the channeled member 34, warming or cooking the frankfurters in the frame 23.

From the foregoing it will be evident that the sandwich-making device of the invention is unitary and self-contained, the food articles therein being completely enclosed so as to be kept clean. The device is light and compact, and therefore may be carried easily from place to place, and in this connection it is to be noted that the device may be strapped to the operator's shoulders and easily operated while so supported. Another advantage of the device is that it comprises few parts and is easily cleaned.

While the preferred embodiment of the invention is described herein and illustrated in the drawings, various modifications and changes may be made within the principles of the invention and the scope of the claims.

What I claim is:

1. In a sandwich-making device, a first frame having two annular and concentric series of elongated compartments open at both ends adapted to house frankfurters, a second frame having two annular and concentric series of elongated compartments open at both ends adapted to house frankfurter rolls, said frames being axially aligned and spaced apart, sandwich-assembling means between the frames, means supporting the frames for rotation and supporting the sandwich-assembling means, and means selectively slidably in each frame compartment feeding the respective food articles to the sandwich-assembling means, said slidable means comprising a plurality of plungers

slidable toward and away from said sandwich-assembling means.

2. In a sandwich-making device, a first frame having two annular and concentric series of elongated compartments open at both ends adapted to house frankfurters, a second frame having two annular and concentric series of elongated compartments open at both ends adapted to house frankfurter rolls, said frames being axially aligned and spaced apart, sandwich-assembling means between the frames, means supporting the frames for rotation and supporting the sandwich-assembling means, and means selectively slidable in each frame compartment feeding the respective food articles to the sandwich-assembling means, said slidable means comprising a plurality of plungers slidable toward and away from said sandwich-assembling means, said means supporting the frames comprising a casing and a shaft journaled in the latter on which the frames are rotatable.

3. In a device such as described, sandwich-assembling means for rolls and frankfurters, said means comprising an elongated trough-shaped part having an opening at each end thereof, and a plate part disposed over the trough-shaped part, one of said parts having a horizontally disposed U-shaped flange approximately centrally thereof and extending longitudinally of the trough-shaped part opening a roll lengthwise when the roll is inserted in the trough-shaped part through one end thereof, and the flange guiding a frankfurter into the opened roll when the frankfurter is inserted in the trough-shaped part through the other end thereof.

4. In a device such as described, sandwich-assembling means for rolls and frankfurters, said means comprising an elongated trough-shaped part having an opening at each end thereof, and a plate part disposed over the trough-shaped part, one of said parts having a horizontally disposed U-shaped flange approximately centrally thereof and extending longitudinally of the trough-shaped part opening a roll lengthwise when the roll is inserted in the trough-shaped part through one end thereof, and the flange guiding a frankfurter into the opened roll when the frankfurter is inserted in the trough-shaped part through the other end thereof, the plate part being detachable from the trough-shaped part.

5. In a device such as described, a container providing a reservoir for rolls, a container providing a reservoir for frankfurters, sandwich-assembling means between the containers, and means feeding rolls and frankfurters to the sandwich-assembling means from the respective reservoirs, said sandwich-assembling means comprising an elongated trough-shaped part and a plate part disposed over the trough-shaped part, the trough-shaped part having an opening at each end thereof, one of said parts having a horizontally disposed U-shaped flange approximately centrally thereof and extending longitudinally of the trough-shaped part opening a roll lengthwise when the roll is fed into the trough-shaped part through one end thereof, and the flange guiding a frankfurter into the opened roll when the frankfurter is fed into the trough-shaped part through the other end thereof.

6. In a device such as described, sandwich-assembling means for rolls and frankfurters, said means comprising an elongated trough-shaped part and a plate part disposed over the trough-shaped part, the trough-shaped part having an opening at each end thereof, the plate part having a horizontally disposed U-shaped flange approximately centrally thereof and extending longitudinally of the trough-shaped part opening a roll lengthwise when the roll is inserted in the trough-shaped part through one end thereof, and the flange guiding a frankfurter into the opened roll when the frankfurter is inserted into the trough-shaped part through the other end thereof.

7. In a device such as described, a fixed drum, a frame rotatable in the drum presenting concentric series of compartments for food articles, said compartments being open at the ends and the ends being disposed toward the drum ends, means for rotating the frame, a plunger for each compartment series slidable in one end of the drum and movable lengthwise in a selected compartment to feed the article toward and through the opposite end of the drum, and an assembly means exteriorly of said opposite end to receive the food article.

8. In a device such as described, a fixed drum, a frame rotatable in the drum presenting concentric series of compartments for food articles, said compartments being

open at the ends and the ends being disposed toward the drum ends, means for rotating the frame, a plunger for each compartment series slidable in one end of the drum and movable lengthwise in a selected compartment to feed the article toward and through the opposite end of the drum, an assembly means exteriorly of said opposite end to receive the food article, and means connected to the drum and engageable with the frame to align said compartments with their respective plungers.

9. In a device such as described, a fixed drum, a frame rotatable in the drum presenting concentric series of compartments for food articles, said compartments being open at the ends and the ends being disposed toward the drum ends, means for rotating the frame, a plunger for each compartment series slidable in one end of the drum and movable lengthwise in a selected compartment to feed the article toward and through the opposite end of the drum, an assembly means exteriorly of said opposite end to receive the food article, and means connected to the drum and engageable with the frame to align said compartments with their respective plungers, said assembly means being movable so as to be aligned with any one of said plungers.

10. In a sandwich-making device, a portable casing providing two drums axially aligned and spaced apart, means providing a chamber between the drums, a shaft extending through said drums and journaled therein, a first frame fixed to said shaft in one of said drums and having two annular and concentric series of elongated compartments open at both ends adapted to house frankfurters, a second frame fixed to said shaft in the other of said drums and having two annular and concentric series of elongated compartments open at both ends adapted to house frankfurter rolls, means at one end of said shaft to rotate the latter, sandwich-assembling means in said chamber, and means selectively slidable in each frame compartment feeding the respective food articles to the sandwich-assembling means.

11. In a sandwich-making device, a casing, a frame revolvably mounted in the casing having two annular and concentric series of elongated compartments open at both ends and each adapted to house a frankfurter, a second frame revolvably mounted in the casing in axially aligned and spaced relation to the first frame, the second frame having two annular and concentric series of elongated compartments open at both ends and each adapted to house a frankfurter, the compartments of one of said frames being substantially in alignment with the compartments of the other frame, means supported from the casing providing two sandwich-assembling stations between said frames, one station being substantially in alignment with each series of compartments in one of said frames, sandwich-assembling means selectively movable from one of said stations to the other, means to rotate said frames, and means feeding the respective food articles to the sandwich-assembling means, said last-mentioned means comprising four plungers, one plunger cooperating with each series of food compartments and the plungers being slidably mounted in the casing and being adapted to push the respective food articles to the sandwich-assembling means.

12. In a sandwich-making device, a casing, two frames in the casing each having two annular and concentric series of elongated compartments open at both ends, the compartments of one frame being adapted to house frankfurters and the compartments of the other being adapted to house frankfurter rolls, a shaft mounting the frames from the casing for rotative movement with the shaft, the frames being spaced apart and the compartments of one of said frames being substantially in alignment with the compartments of the other frame, means supported from the casing providing two sandwich-assembling stations between said frames, one station being substantially in alignment with each series of compartments in one of said frames, sandwich-assembling means selectively movable from one of said stations to the other, means to rotate said frames, and means feeding the respective food articles to the sandwich-assembling means, said last-mentioned means comprising four plungers, one plunger cooperating with each series of food compartments, and the plungers being slidably mounted in the casing and being adapted to push the respective food articles to the sandwich-assembling means.
